SHOE HANGER

Deborah E. Sussman, 11632 San Vicente Blvd.,
Los Angeles, Calif. 90049

Filed Aug. 4, 1969, Ser. No. 18,515

Term of patent 14 years

Int. Cl. D6—07

U.S. Cl. D80—8

Fig. 9

Fig. 10

Fig. 12

Fig. 13

Fig. 15

Fig. 16

Fig. 17

FIG. 1 is a perspective view of a shoe hanger embodying my new design; the broken line representation of a shoe is for purposes of illustration only;

FIG. 2 is a side elevation view thereof;

FIG. 3 is an end elevation view thereof as viewed from the right of FIG. 2;

FIG. 4 is a top plan view thereof;

FIG. 5 is a perspective view of a modified form of the shoe hanger as shown in FIG. 1;

FIG. 6 is a side elevation view of FIG. 5;

FIG. 7 is an end elevation view of FIG. 5;

FIG. 8 is a top plan view of FIG. 5;

FIG. 9 is a side elevation view of the second modified form of the shoe hanger as shown in FIG. 1;

FIG. 10 is an end elevation view of FIG. 9;

FIG. 11 is a top plan view of FIG. 9;

FIG. 12 is a side elevation view of the third modified form of the shoe hanger as shown in FIG. 1;

FIG. 13 is an end elevation view of FIG. 12;

FIG. 14 is a top plan view of FIG. 12;
FIG. 15 is a side elevation view of the fourth modified form of the shoe hanger as shown in FIG. 1;

FIG. 16 is an end elevation view of FIG. 15; and

FIG. 17 is a top plan view of FIG. 15.

I claim:

The ornamental design for a shoe hanger, as shown.
